CLAIM

The ornamental design for a combined dry shaver,
cover, and brush, substantially as shown and described.

DESCRIPTION

FIG. 1 is a right front perspective view of a combined dry shaver, cover, and brush showing my new design with the cover and brush removed;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a right front perspective view of the shaver with the cover and brush in place;

FIG. 9 is a rear left perspective view thereof; and

FIG. 10 is a left side elevational view thereof.
